Primary Examiner — Mitchell I. Siegel

(74) Attorney, Agent, or Firm — Randy K. Chang

(57) **CLAIM**

The ornamental design for wedge golf club, as shown and described.

DESCRIPTION

FIG. 1 is a perspective back view of my new design for a wedge golf club;

FIG. 2 is a back view thereof;

FIG. 3 is a top view thereof;

FIG. 4 is a bottom view thereof;

FIG. 5 is a heel view thereof;

FIG. 6 is a toe view thereof; and,

FIG. 7 is a front view thereof.

The broken line showing of the horizontal grooves on the striking face is included for the purpose of illustrating and forms no part of the claimed design.

1 Claim, 4 Drawing Sheets# US D829,837 S
